SWIVELING ARBOR SUPPORT

Filed Oct. 14, 1927

UNITED STATES PATENT OFFICE

PAUL LIEBSCHER, OF CHEMNITZ-GABELN, GERMANY

SWIVELING ARBOR SUPPORT

Application filed October 14, 1927. Serial No. 226,085.

This invention relates to metal working machines in which a cutter or work spindle is provided with an end support bearing, it particularly relating to gear-cutting and 5 milling machines, the object of the invention being to provide an improved spindle supporting member for such a machine.

Arbor supports on different kinds of milling machines, including gear cutters, have 10 been in use for a considerable length of time. The purpose of such supports is to provide an outer bearing on the work arbor and thus increase its rigidity, eliminate vibration, etc. There are several types of such arbor supports known which can be divided principally in two classes: a rigid support and a side swiveling support. Both types have certain advantages. The rigid type which is usually made of a box-shaped casting furnishes greater rigidity, while the side swiveling type provides greater convenience in operation due to the fact that the arm containing the outer bearing can be swung sideways out of the way. The application of a side 20 swiveling arbor support was probably first used on horizontal milling machines in such a way that the support consisted of a cylindrical shaft carrying the arm in a cylindrical bearing. The arm when not in use could then be 30 swung out of the way in a plane at right angles to the axis of the support. To make such swiveling arbor supports more rigid, the support itself was later on made in box form, but this necessitated the introduction 35 of a vertically pivoted member between the arm and column support which impaired the rigidity of this swiveling box type of support to a certain extent, although it permitted the side swivelling of the arm in a plane at right angles to the axis of the support.

In the present improvement the pivotal or swinging arbor support is so connected with the supporting column that it may be 45 swung vertically to a position in alignment with the supporting column, so that it is entirely out of the way, which is not always the case with that type of support, where the supporting arbor is swung sideways or at 50 right angles to the column or support, the

present improvement not interfering with the necessary rigidity of the structure.

In the drawings accompanying and forming a part of this specification,—

Fig. 1 is a side elevation of this improved spindle-supporting means;

Fig. 2 is a top view thereof;

Fig. 3 is a perspective detail view of the upper part of the column or support;

Fig. 4 is a detail view of the gear mechanism for raising and lowering the supporting arm; and

Fig. 5 is a view illustrating the manner in which the supporting arbor may be applied to a milling machine.

Similar characters of reference indicate corresponding parts in the several figures of the drawings.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description, and not of limitation.

In the structure shown in Figs. 1 to 4, which is particularly adapted to support the work spindle of a gear-cutting machine, a box-type form of column is provided which may be secured in any suitable way to a base, and this column is formed as a two-part structure, the top or head member 3 thereof being horizontally pivoted by journals 4 to the top of the lower part or base 2 of the column so that the part 3 may be swung in a vertical direction toward or from the face or front of the column. When swung vertically upward a part of the head member 3 will swing within the recessed or bifurcated top portion 2' (see Fig. 2) of the column 2, as indicated by dotted lines in Fig. 1, suitable clamping means 5 being provided for holding the vertically swinging member 3 in either its working or non-working position. The face or forward side of the swinging head member 3 and base 2 of the column are provided with aligned guideways 6 and 7 for the

100

reception of the supporting arm 8 adapted to be clamped thereto by suitable clamping straps or gibbs 9 and bolts whereby the supporting arm may be raised or lowered, as occasion may require. The arm 8 is provided with an opening 10 coaxial with the work spindle to be supported. For the purpose of raising and lowering the arm 8 upon its guideways suitable gearing is provided and in the present instance the top and bottom members 10 of the column are provided with aligned racks 11 and 12 in mesh with which is a worm gear 13 carried by the supporting arm 8 having a bevelled gear 14 in mesh with a companion bevelled gear 15 carried by a hand wheel shaft 16 on the outer end of which is a hand wheel 17. The rotation of this hand wheel rotates the worm gear 13 and thereby raises and lowers the arm 8. When it is desired 20 to swing the arm 8 out of the way it is unclamped from the base 2 of the column and shifted upwardly by the means described, so as to engage the head or top part 3 of the column, whereupon the arm of the column 25 head 3 may be thrown upward into the position shown in dotted lines in Fig. 1, so that it is entirely out of the way and in this position it may be clamped by the clamping means 5. The arm 8 and the head part 30 of the column at this time rest upon the base 2 of the column. When it is desired to use the arm again it is merely necessary to unclamp the clamping means 5, throw the arm and column head downward upon its journals 35 4 and then operate the hand wheel to shift the arm into any desired position to receive the spindle or arbor as shown in full lines in Fig. 1.

The present improvement is also adapted 40 for use in milling machines in which the support is likewise made in two parts 2" and 3' pivotally secured together so that the part 3' may be swung vertically, said parts 2" and 3' being provided with a slideway 4' for the 45 reception of an arbor-supporting member 5' so that when this member 5' is moved onto the guideway of the part 3' the same may be swung upward in the manner heretofore described in connection with Figs. 1 to 4, thereby releasing the arbor or spindle of the 50 milling cutter 15.

It is to be understood that by describing in detail herein any particular form, structure, or arrangement, it is not intended to limit 55 the invention beyond the terms of the several claims or the requirements of the prior art.

Having thus explained the nature of my 60 said invention and described a way of constructing and using the same, although without attempting to set forth all of the forms in which it may be made or all of the modes of its use, I claim:

1. The combination of a supporting member 65 and a supporting arm having a free forward end, the former comprising a two-part

member having a horizontal pivotal connection whereby one part is swingable vertically relatively to the other, the arm being adjustable on said supporting member and shiftable with the swingable part of said supporting member in the direction of the length of 70 said supporting member so as to free all of the sides of said supporting member of any transverse obstruction to the handling of the work. 75

2. The combination of a supporting column and a supporting arm having a free forward end, said column comprising a base and a top, the latter being horizontally pivoted to the base for swinging movement in a vertical plane and the arm being adjustable on said supporting member whereby it may be shifted vertically with said top in the direction of the length of said supporting column so as to free 80 all of the sides of said supporting column of 85 any transverse obstruction to the handling of the work.

3. The combination of a box-type supporting column comprising a two-part structure consisting of a base and a horizontally pivoted head shiftable in a vertical plane, and a supporting arm having a free forward end and adjustably carried by said column whereby in one position thereof it may be shifted vertically with the head in the direction of the length of said supporting column so as to free 90 all of the sides of said supporting column of any transverse obstruction to the handling of the work. 95

4. The combination of a box-type supporting column comprising a base and a vertically shiftable top horizontally pivoted to said base, said base and top having guideways, a vertically adjustable arm having a free forward end and carried on said guideways and 100 means for adjusting said arm whereby in one position thereof it may be vertically shifted with said top in the direction of the length of said supporting column so as to free all of the sides of said supporting column of any transverse obstruction to the handling of the work. 105

5. The combination of a hollow box-type supporting column comprising a base and a pivoted vertically shiftable top adapted in one position thereof to have a part thereof project into the base, an adjustable arm having a free forward end, means carried by said column for supporting said arm, and means for adjusting the arm relatively to the column whereby in one position thereof it may be shifted vertically with the top. 115 120

6. The combination of a supporting member comprising a base having a recessed top, a head pivoted in said recessed top for swinging movement in a vertical plane, guideways carried by said base and head, an arm having a free forward end and adjustably mounted on said guideways and means for shifting said arm whereby in one position thereof it may be shifted vertically with the head in 125 130

the direction of the length of said supporting member so as to free all of the sides of said supporting member of any transverse obstruction to the handling of the work.

7. The combination of a box-type supporting member having a base and a top horizontally pivotally connected thereto, whereby the top may be swung in a vertical direction, a bearing arm having a free forward end and adjustably mounted upon said supporting member and adapted in one position thereof to be swung with the top in a vertical direction in the direction of the length of said supporting member so as to free all of the sides of said supporting member of any transverse obstruction to the handling of the work, and means for clamping said top and bearing arm when swung upward.

8. The combination of a two-part supporting member permanently pivotally connected crosswise of the end of one of said members for swiveled movement of one member relatively to the other, said members having alined guideways, and a supporting arm having a free forward end and shiftable along said alined guideways and swingable with the swiveled member transversely of the length of said supporting member in the direction of the length of said supporting member so as to free all of the sides of said supporting member of any transverse obstruction to the handling of the work.

9. The combination of a two-part upright supporting member permanently pivotally connected crosswise of the top of one of said members for swiveled movement of one member relatively to the other, said members having alined guideways, and a supporting arm having a free forward end and shiftable along said alined guideways of the supporting member and swingable with the swiveled member transversely of the length of said supporting member in the direction of the length of said supporting member so as to free all of the sides of said supporting member of any transverse obstruction to the handling of the work.

10. The combination of a supporting member comprising a pair of members permanently pivotally connected transversely of the length thereof for swiveled movement of one member relatively to the other, said members having alined guideways, and a supporting arm having a free forward end and having integral therewith a co-operating guideway, whereby it is shiftable along the alined guideways of the supporting member and swingable with the swiveled member transversely of the length of said supporting member in the direction of the length of said supporting member so as to free all of the sides of said supporting member of any transverse obstruction to the handling of the work.

11. The combination of a two-part upright supporting member pivotally connected cross-

wise of the top of one of said members for swiveled movement of one member in a vertical plane relatively to the other, said members having alined guideways, and a supporting arm having a free forward end and having integral therewith a co-operating guideway, whereby it is shiftable along the alined guideways of the supporting member and swingable with the swiveled member in a vertical plane transversely of the length of said supporting member in the direction of the length of said supporting member so as to free all of the sides of said supporting member of any transverse obstruction to the handling of the work.

12. The combination of a two-part upright supporting member pivotally connected crosswise of the top of one of said members for swiveled movement of one member in a vertical plane relatively to the other, one of said members having a bifurcated end for the reception of a part of the other member, said members having alined guideways, and a supporting arm having a free forward end and having integral therewith a co-operating guideway, whereby it is shiftable along the alined guideways of the supporting member and swingable with the swiveled member in a vertical plane transversely of the length of said supporting member.

13. The combination of a two-part supporting member comprising a pair of members permanently pivotally connected crosswise of the length thereof for swinging movement of one member relatively to the other to bring the juxtaposed portions of said two-part supporting member into overlapping relation, said members having alined guideways at the working face of the supporting member, and a supporting arm having a free forward end and shiftable along said alined guideways and swingable with the swinging member in the direction of the length of the supporting member to extend entirely above the guideways of said supporting member thereby to free all of the sides of said supporting member of any transverse obstruction to the handling of the work.

Signed at Chemnitz this 23d day of September, 1927.

PAUL LIEBSCHER.
